CLAIM

The ornamental design for eyewear, as shown and described.

DESCRIPTION

FIG. 1 is a front elevational view of the eyewear showing my new design;

FIG. 2 is a side elevational view thereof, the opposite side being a mirror image;

FIG. 3 is a rear elevational view thereof;

FIG. 4 is a bottom plan view thereof;

FIG. 5 is a reduced top plan view thereof with the temples shown pivoted in an inoperative, vertical position.

FIG.1
